UNITED STATES PATENT OFFICE.

ARTHUR J. STONE, OF GARDNER, MASSACHUSETTS, ASSIGNOR TO FRANK W. SMITH, OF SAME PLACE.

DESIGN FOR A SPOON, &c.

SPECIFICATION forming part of Design No. 21,268, dated December 29, 1891.

Application filed October 29, 1891. Serial No. 410,282. Term of patent 3½ years.

To all whom it may concern:

Be it known that I, ARTHUR J. STONE, a citizen of the United States, residing at Gardner, in the county of Worcester and State of Massachusetts, have invented and produced a new and original Design for Handles for Spoons, Forks, Knives, and the Like, of which the following is a specification, reference being had to the accompanying drawing, showing a handle containing my said design, the handle being for spoons, forks, knives, and the like.

My design consists of a handle of irregular outline, with marginal and shank ornamentation of scroll and conventionalized leaf work, as shown in the drawing and more fully described below.

The shank a curves from near its inner end outwardly to the side projections a' a'' . Beyond projection a' upon that edge x of the handle the edge is indented at a^3 , a^4 , a^5 , a^6 , and a^7 and curved by curves a^8 of different lengths to make edge x irregular in outline, as shown. The edge x' is also of irregular outline, being indented at a^9 , a^{10} , and a^{11} and curved by a series of curves a^{12} . The upper

or outer end of that curve a^8 nearest the butt-end of the handle curves inwardly to indentation a^7 , and the upper or outer end of that curve a^{12} nearest the butt-end of the handle curves outwardly to projection a^{13} . The butt-end portion a^{14} of the handle, which is between the indentation a^7 and projection a^{13} , is substantially a projection and its outline is irregular. This part a^{14} is marginally ornamented by a conventionalized leaf a^{15} , and each side margin of the handle is ornamented with irregular scroll-work a^{16} , leaving a plain surface b of irregular outline, which is bounded by the leaf a^{15} , marginal scroll-work a^{16} , and conventionalized feather-work a^{17} between the marginal scroll-work a^{16} , which extends to the projections a' a'' .

What I claim is—

The design for a handle for spoons, forks, knives, and the like, as herein shown and described.

ARTHUR J. STONE.
